GOLF CLUB HEAD

Henry C. Timbrook, Miami, Fla., assignor to
Touring Pro, Ltd., New York, N.Y.

Filed Oct. 21, 1974, Ser. No. 516,261

Term of patent 14 years

Int. Cl. D21—02

U.S. Cl. D34—5 GH

FIG. 1 is a top plan view of a golf club head showing my new design;

FIG. 2 is a rear elevational view thereof;

FIG. 3 is a left side view thereof;

FIG. 4 is a bottom plan view thereof; and

FIG. 5 is a front elevational view.

I claim:

The ornamental design for a golf club head, as shown and described.
